(57) CLAIM

The ornamental design for a nursing garment, as shown and described.

DESCRIPTION

FIG. 1 is a front view of the obverse side of a nursing garment showing my new design; and,

FIG. 2 is a front view of the reverse side of the nursing garment thereof.

The broken lines shown in the figures are included for the purpose of illustrating portions of the nursing garment that form no part of the claimed design.

1 Claim, 2 Drawing Sheets Fig. 1

Fig. 2
